United States Patent Office

Des. 210,691

Patented Apr. 2, 1968

210,691

PAPER CUTTER

David O. Chase, Camillus, Philip H. Stevens, Syracuse, and Alan W. Brownlie, Skaneateles, N.Y., and John A.
Malm, Rocky River, Ohio, assignors to The Chandler
& Price Company, Cleveland, Ohio, a corporation of Ohio

Filed Nov. 3, 1966, Ser. No. 4,542

Term of patent 14 years

(Cl. D55—1)

FIG. 1

FIG. 2

FIG. 3

FIG. 4

FIG. 5

FIG. 1 is a top plan view of a paper cutter embodying our new design;

FIG. 2 is a front elevation thereof;

FIG. 3 is a side elevation thereof as seen from the right in FIGS. 1 and 2;

FIG. 4 is an opposite side elevation thereof as seen from the left in FIGS. 1 and 2;

FIG. 5 is a rear elevation thereof.

We claim:

The ornamental design for a paper cutter, as shown and described.
